UNITED STATES PATENT OFFICE.

ROBERT C. REDPATH, OF OLATHE, KANSAS.

ROAD GRADER.

Application filed September 4, 1923. Serial No. 660,739.

To all whom it may concern:

Be it known that I, ROBERT C. REDPATH, a citizen of the United States, residing at Olathe, county of Johnson, in the State of Kansas, have invented a certain new and useful Improvement in Road Graders, of which the following is a complete specification.

This invention relates to road graders and has for its prime object to produce a machine in which the drag element is utilized as the support for the blade and so related to the framework that up and down movement of the latter cannot affect the blade which, therefore, cuts off humps or raised parts and clears or passes freely over low places in the roadway.

Another object is to provide means for raising the blade to inoperative position when it is desired to utilize the drag alone.

A still further object is to provide means for adjusting the drag element to an inclined position to permit of the passage of the rear portion over the ground without contact therewith, as for example where it is undesirable to increase the height of the crown line of the road.

With the objects named in view, the invention consists in certain novel and useful features of construction and organization of parts as hereinafter described and claimed; and in order that it may be fully understood, reference is to be had to the accompanying drawings, in which:—

Figure 1 is a side view of a machine embodying the invention;

Figure 2 is an enlarged face view of the drag and cutting blade forming a part of the invention, partly broken away to illustrate parts otherwise hidden;

Figure 3 is a top plan view of the machine.

Figure 4 is an enlarged section on the line IV—IV of Figure 3.

In the said drawings, where like reference characters identify corresponding parts in all of the figures, 1 represents longitudinal members of a tractor or other suitable frame, said frame members being journaled on an axle 2 supported by a pair of tractor wheels 3. The side frame members 1 are secured together at their rear ends by a cross frame 4 which projects some distance beyond one of the sides (see Figure 2) and at a suitable point forward of the axle one of the

side frame members 1 is provided with an outwardly projecting arm 5 which, in conjunction with the projecting end of the cross frame 4, provides suitable securing means for a longitudinal bar 6 parallel to the frame members 1. Projecting at right angles to the bar 6 are a pair of bars 7, which are secured together at their extremities by a longitudinal bar 8. All of the parts heretofore described are combined to provide a rigid and strong framework for certain operative parts hereinafter described, and it is to be understood in this connection, however, that any suitable sort of properly braced framework may be employed.

Depending from the bar 6 at a point substantially in line with the axle of the carrying wheels 3 is a pull post 9, and in substantially transverse alignment therewith and depending from the member 8 is a similar pull post 10, said posts being braced by brace members 11.

Secured to the lower end of the post 10 is a short length of pull chain 12 secured at its free end to one end of a drag beam 13 of any suitable or preferred length and material. At a point relatively close to the end to which the pull chain is secured, the drag 13, which is illustrated as of channel iron form, is provided with a suitable filler block 14 to which is secured a channel bracket 15, provided with outwardly projecting ears 16. The ears 16 are formed with registering openings for pivotal reception of the vertical portion of a right-angle shaped arm 17, reduced at its lower end as at 17 to provide a shoulder 18 for abutment against lower ear 16 of the bracket 15, to prevent upward movement of the drag on the arm 17. A washer 20 is fitted on the reduced end of the arm 17, and said drag is retained in position by means of a pin 21 underlying the washer.

The other end of the right-angle shaped arm 17 is pivotally secured to a headed pin 22 rearwardly projecting from the depending post 9. In this connection it will be apparent that the arm 17 will counteract all tendency of the adjacent end of the drag 13 to move rearwardly, and that the pull chain 12 will receive the entire angular or dragging strain.

In order to maintain the rear end of the drag 13 in proper position, and also to pro-

vide means whereby it may be raised from contact with the ground, it is provided at a suitable point with a filler block 23, to which a channel iron bracket 24, similar to the bracket 15, is secured, and fastened to said bracket 24 in a manner similar to that described in connection with the arm 17, is a right angle shaped arm 25 formed with a series of perforations in its end, and said end of the arm is received within a perforated sleeve member 26 and is fixed in such position by means of a pin 27 engaging registering perforations in the sleeve and arm. The other end of the sleeve 26 is rigidly secured in any suitable manner to an arm 28 which is provided with an eye or loop in its end slidingly engaged on a keeper 29 secured to one of the frame members 1, see Figure 1.

From the construction above-described, it will be apparent that the drag is free to follow the surface of the ground irrespective of the vertical movements of the carrying wheels 3 and the framework of the machine, as the drag will be free for up and down movements, the ends of arms 17 and 28 having limited vertical pivotal movement on pin 22 and keeper 29, respectively. It will also be evident that as the arms 17 and 25 have pivotal connection with the drag beam, the angle of the drag with respect to the machine may be adjusted as found desirable through use of the telescopic connection between arm 25 and sleeve 26.

In order to provide means whereby the ends of the drag may be elevated as found desirable, either to accommodate crowns of varying pitch or for transportation, a short length of chain 30 is connected to the arm 25, the other end of said chain being secured to one end of a rocker bar 31 which is centrally mounted on an extension 32 rearwardly projecting from the main framework. The other end of the rocker bar 31 is headed and projects through a slot 33 formed in an operating lever 34 mounted on a headed pin 35 carried by the framework 1. The opposite end of the lever is formed with a handle 36 which is in convenient position for operation by the operator of the machine who will normally stand on a platform 37 carried by the drag beam. It will be evident that if downward movement is applied to the lever 34, that through the connections described, the rear end of the drag will be raised from contact with the road. If it is desired to maintain the rear end of the drag in its elevated position, a short length of the chain 38 secured to an extension 39 rearwardly projecting from the framework is temporarily engaged with the handle 36.

In order to provide means for the elevation of the front end of the drag, a short shaft 40 is journaled in the rearwardly pro-

jecting end of the frame member 8 and in an arm 41 carried by the frame member 7, said shaft being provided at one end with an operating wheel 42 equipped with a gravity dog mechanism 43 for maintaining the shaft in any desired position of adjustment. Secured to the front end of the beam 13 is one end of a lifting chain 44, the other end thereof being engaged with a shaft 40 as will be readily understood. From the above description, it will be evident, that the lifting devices for the beam are of an extremely flexible nature and will not, therefore, interfere with the vertical movements of the drag in following the irregularities of the roadway.

In order to provide scraping or leveling means whereby the surface of the roadway may be smoothed, regardless of the up and down movements of the supporting wheels and framework, I have found it desirable to attach a cutting blade 45 directly to the drag beam 13, and also to provide means for adjusting said blade to regulate the depth of cut or to elevate the same when it is desired to use the drag alone.

The blade 45 is secured to and projects some distance beyond the front end of the drag in a convenient position for the production of a drainage ditch or the like, along the side of the road, the dirt cut by said blade traveling therealong and being transferred from its rear end to the drag by which it is distributed over the road and fills up the low places therein as common in the art.

The attaching and regulating means for the blade are as follows: Secured to the rear of the blade near its front end are two series of ears 46 and 47 in vertical alignment and rigidly secured to the stem of a T-shaped iron 48 adapted for vertical reciprocation transversely of the face of the drag 13 and held in position against the drag by means of a pair of guides 49. The upper end of the T-iron is secured to a link 50, pivotally secured at its other end to an operating lever 51 fulcrumed in a standard 52 carried by the drag 13, and being equipped with any suitable latch mechanism 53 for cooperation with a sector 54 upwardly projecting from the drag, whereby the front end of the blade may be vertically adjusted to regulate the depth of cut. In this connection it is desirable to point out that the T-iron 48 fits loosely in the guides 49 so as to accommodate tilting of the blade pending its vertical adjustment, as will hereinafter appear.

Secured to the rear side of the other end of the blade are two pairs of ears 55 between the extremities of which is rigidly secured a vertical bar 56, said bar abutting against the face of the drag 13 and being received within a longitudinal strap guide 57 rigidly

secured to said drag about midway its width. The strap is of such length as to allow of relatively great tilting movement of the blade with respect to the beam to permit the 5 forward end of the blade to be inclined downwardly, see the dotted lines Figure 4, for the production of a ditch or the like along the side of the road. Secured to the upper end of the bar 56 is a link 58 pivotally connected at its upper end to an operating lever 59 which is fulcrumed at its end in a standard 60 secured to the drag. The lever 59 is provided with any suitable latch mechanism 61 for cooperation with a sector 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300

It is thought no further recapitulation of the operation of the device is necessary, other than to point out that the fact that 20 as the beam is entirely free to follow the irregularities of the road regardless of the movements of the supporting wheels and framework, the operation of the cutting blade carried thereby will be even, the depth 25 of cut being regulated through the levers 51 and 59 and being maintained through the fact that the blade is carried by the drag.

It will be evident from the construction 30 above described that the blade may be lifted from contact with the ground when found desirable, and that the beam may also be elevated and adjusted both vertically and longitudinally to accommodate work of varying character and under different conditions, and 35 also that when the drag is elevated the

blade is also necessarily elevated as it is carried thereby.

From the above description, it will be apparent that I have produced a machine of the character described which possesses all 40 of the features of advantage set forth as desirable, and while I have described and claimed the preferred embodiment of the same, I reserve the right to make all changes 45 properly falling within the spirit and scope of the appended claims.

I claim:

1. In a machine of the character described, the combination of a wheeled-frame, a pair 50 of arms pivotally secured to said wheeled-frame, a drag beam pivotally secured to the ends of said arms, one of said arms being adjustable in length, means for elevating said beam from the roadway, and a vertically-adjustable cutting blade carried by 55 said beam.

2. In a machine of the character described, the combination of a wheeled-frame, a pair of arms pivotally secured to said 60 wheeled-frame, a drag beam pivotally secured to the ends of said arms, one of said arms being adjustable in length, independent elevating means for each end of said drag beam, a cutting blade carried by said beam, and independent elevating means for each end 65 of said blade.

In witness whereof I hereunto affix my signature.

ROBERT C. REDPATH.
